GARMENT BAG

Albert J. Rassenfoss, Evanston, Ill.

Application February 19, 1930, Serial No. 429,489

3 Claims. (Cl. 206—7)

The invention relates to improvements in garment bags of the type having a central orifice in the top for the protrusion of the suspending hook of a garment hanger, the primary object of the 5 invention being to provide improved means for sealing said orifice and reinforcing the top of the bag.

Other objects will appear hereinafter.

The invention consists in the combinations and 10 arrangements of parts hereinafter described and claimed.

The invention will be best understood by reference to the accompanying drawing forming a part of this specification, and in which

15 Fig. 1 is a front view of a bag embodying the invention showing the sealing means as provided on the bag before sealing thereof, one of said sealing flaps being shown as folded back to exhibit the underlying parts;

20 Fig. 2 a similar view showing the bag sealed; Fig. 3 a view showing the sealing means after one of the sealing flaps has been secured;

Fig. 4 a similar view showing the sealing flap after the other sealing flap has been secured; and

25 Fig. 5 a view of the sealing sticker detached.

The embodiment of the invention illustrated in the drawing comprises the usual tubular bag 10, preferably of paper or similar material, and having the usual fold or flap 11 at the bottom for sealing the same after the garment is inserted 30 therein. The top of the bag is also provided with the usual folded flaps 13 arranged as shown to provide a central orifice 14 and a top edge 15 inclined or sloping downwardly at each side of said orifice.

35 A sticker member 16, which is preferably made of cloth or other flexible tough material having adhesive on one face, is employed for sealing and reinforcing the upper edge of the bag. This 40 sticker member may be substantially in the form indicated in Fig. 5, having one portion foldable along the line 17 and the other portion slotted at 18. The said one portion of the sticker member 16 is folded along the line 17 and adhesively secured to both the front and the rear of the bag at one side of the orifice 14 as indicated. By 45 this arrangement, substantially one-half of the orifice 14 will be closed and sealing flaps 19 and 20 provided for sealing the remaining portion of said orifice 14 after the hook 21 of the garment hanger is inserted as shown through the orifice 14. After this has been done, the flap 19 may be moistened and folded over the corresponding top edge of the bag to close and seal the orifice 14. Then 55 the other sealing flap 20 is moistened and folded over the flap 19 to further seal the orifice and reinforce the top of the bag. By this arrangement, a perfect seal is provided for the orifice 14 and at the same time the top of the bag is reinforced. It will be noted that the sticker member

16 is circular in form so that when completely utilized, as indicated in Fig. 4 of the drawing, a uniform circular reinforcing sealing element is formed around the orifice in the bag, thereby providing an efficient, durable, reinforcing, and ornamental seal for the bag. 65

The bottom of the bag is closed in the usual way by means of the fold or flap 11.

In this manner a garment bag is provided which is perfectly sealed against the entry of moths or 70 the like and at the same time the top edge thereof is suitably reinforced.

While I have illustrated and described the preferred form of construction for carrying my invention into effect, this is capable of variation and modification without departing from the spirit 75 of the invention. I therefore do not wish to be limited to the precise details disclosed, but desire to avail myself of such variations and modifications as fall within the scope of the appended 80 claims.

Having thus fully described my invention, what I claim as new and desire to secure by Letters Patent is:

1. A garment bag having a central orifice at its top; and a sticker having one portion folded over the top edge of said bag at one side of said orifice and there secured to said bag at both front and rear, the other portion of said sticker being slotted substantially in line with said fold to form flaps arranged at front and rear of said orifice, the rear flap being foldable over said top edge to be secured to the front of the bag and the front flap foldable over said top edge to be secured to the rear of the bag. 85

2. A garment bag having a central orifice and a top edge inclined downwardly each side from said orifice; and a sticker having one portion folded over the top edge of said bag at one side of said orifice and there secured to said bag at both front and rear, the other portion of said sticker being slotted substantially in line with said fold to form flaps arranged at front and rear of said orifice, the rear flap being foldable over said top edge to be secured to the front of the bag and the front flap foldable over said top edge to be secured to the rear of the bag. 90

3. A garment bag having a central orifice and a top edge inclined downwardly each side from said orifice; and a sticker of substantially circular form provided with a radial slit at one side, said sticker having the other side folded over the top edge of said bag at one side of said orifice and there adhesively secured to said bag at both front and rear, the fold in said sticker being in substantial alignment with said slit, said flaps being foldable over the top edges of said bag on the other side of said orifice to be secured to the front and rear of the bag. 105

ALBERT J. RASSENFOSS.
